Primary Examiner—Jeffrey D Asch*Assistant Examiner*—Carla Jobe Wright(74) *Attorney, Agent, or Firm*—Steven M. Reiss(57) **CLAIM**

The ornamental design for a mobile phone, as shown and described.

DESCRIPTION

FIG. 1 is a perspective view of a mobile phone showing our new design; and,

FIG. 2 is a front elevational view thereof.

The broken lines that show the outermost periphery of non-claimed features represent the boundaries of the claimed design. All other broken lines are directed to environment and are for illustrative purposes only. The broken lines and the unshaded regions defined by broken lines form no part of the claimed design.
